UNITED STATES PATENT OFFICE.

JOHN RUSH, OF NORWICH, CONNECTICUT, ASSIGNOR TO SCHWARZENBACH HUBER CO.,
OF WEST HOBOKEN, NEW JERSEY.

TAKE-UP AND GUIDE FOR SHUTTLES.

Application filed January 30, 1924, Serial No. 689,449.

To all whom it may concern:

Be it known that I, JOHN RUSH, a citizen of the United States, and a resident of Norwich, in the county of New London and 5 State of Connecticut, have invented a new and Improved Take-Up and Guide for Shuttles, of which the following is a full, clear, and exact description.

This invention relates generally to improvements in shuttles and particularly to an improved take-up and guide for the thread and has for an object to provide a simplified construction which will automatically place the thread in proper position 15 as it is first drawn through the shuttle.

Another object of the invention is to provide a take-up and guide wherein the thread is automatically brought in contact with the take-up as it moves to its proper threaded 20 position in the guide.

A still further object of the invention is to provide a take-up and guide for shuttles which will readily co-act with automatic mechanism for supplying new quills to the 25 shuttle whereby the thread from the new quill will be automatically threaded properly.

In the accompanying drawing—

Figure 1 is a fragmentary top plan view 30 showing one end of a shuttle with an embodiment of the invention applied thereto.

Figure 2 is a side view of the structure shown in Figure 1.

Figure 3 is a longitudinal vertical sectional view through Figure 1, approximately on line 3—3.

Figure 4 is a transverse sectional view 40 through Figure 2, approximately on line 4—4.

Figure 5 is a transverse sectional view through Figure 2, approximately on line 5—5.

Figure 6 is a transverse sectional view 45 through Figure 2, approximately on line 6—6.

Figure 7 is a longitudinal horizontal sectional view through Figure 3 approximately on line 7—7.

Figure 8 is a detail perspective view showing 50 a thread guide embodying certain features of the invention.

Referring to the accompanying drawing by numerals, 1 indicates a shuttle which is of the usual type and cut away at the front 55 for receiving the thread guiding structure

2 and the take-up structure 3. The thread guiding structure 2 is locked in position by any suitable means, as for instance, the screw 4. The thread guiding structure 2 may be made in one piece or in a number of 60 pieces secured together and when completed includes an end member 5 which acts to hold the thread which comes from the quill in place and also partially as a guide for the thread 6 as it travels to the take-up structure 3 and from thence out through the eye 7. The end member 5 and the vertical side wall 8 merge into a top plate 9 which is somewhat rounded as indicated in Figure 3 and which terminates beyond the thread 65 guide 2. Preferably, a pair of depending members 10 and 11 extend from the end of the top plate 9, said members being spaced apart and acting as guides for guiding the thread as it moves over the outer 70 surface of the end member 5, the top plate 9 and to the guide 2. The top plate 9 is provided with a depending section 12 having a curved edge 13 co-acting with the curved edge 14 of the shuttle 1 for presenting a 80 guide for the thread as it moves to the eye 7. It will be noted that a projection 15 extends into the eye 7 to prevent the accidental return of the thread through the slot 16. 85

In operation, when it is desired to correctly place the thread in the guide 2, the thread is moved down over the outer surface of the end member 5 and also over the guide to members or prongs 10 and 11 whereupon it will pass into the slot 16 and at 90 the same time will slip off the end members 10 and 11 and be engaged by the tension structure 3. As the thread is moved further down the slot 16, it will automatically enter the eye 7 as indicated in Figure 2 95 whereupon it is in correct position for use.

In order that the thread may remain at the upper part of the thread guide 2, a pair of forwardly extending fingers 17 and 18 are provided, said fingers being connected with the bottom part of the thread guide 2. The forward ends of these fingers are beneath and near the prongs 10 and 11 so that as the thread falls off these prongs it will fall on these fingers and be guided over to a point against the tension member 3. This tension member consists preferably of a plurality of fingers 19 pivotally mounted on the rod or pin 20 carried by the shuttle 1. Preferably, these pins are all secured to a 100 110

tubular member 21 so that they will move in unison. Each of these fingers is provided with a partially closed hook 22 which almost forms an eye though it is sufficiently 5 open to permit the thread to enter as indicated in Figure 3 where the thread normally remains during the operation of the shuttle. In order that a proper tension may be provided, an arm 23 is soldered or otherwise 10 rigidly secured to the tubular member 21 and to the upper end of this arm is connected one end of the rubber band 24, the opposite end extending through the aperture 25 to a point near the exterior surface 15 of the shuttle 1. Preferably, the aperture 25 is comparatively small to a point near the surface where it is enlarged for receiving a knot 26 formed in the elastic member 24. Preferably, an ordinary rubber 20 band is used for the elastic member 24, though if desired, some other form of tensioning member may be used, as for instance, an ordinary steel spring. When the thread is in operative position, it extends 25 through the space partially enclosed by wall 8 and end 5 to the eyes or hooks 22 and from these eyes or hooks to the eyes 7 and from thence to the goods being woven. These parts are so arranged that when a 30 new quill is put in the shuttle the thread of the new quill will automatically move to the position shown in Figures 1, 2 and 7 as the shuttle is operated. When the shuttle is moved to the left as shown in Figure 35 1, the thread will be caused to move beneath the end member 5 and over the plate 9 to the member or prong 10. When the shuttle moves back in the opposite direction, the thread will be pulled so as to engage point 40 11 and then slip off so that it may quickly move to its finished threaded position as shown in Figure 2. It will, of course, be understood that this action may be done manually if desired. In automatic looms it 45 is usually performed automatically as the loom discharges an empty quill and receives a full one.

What I claim is:—

1. In a take-up and guide for shuttles, a 50 take-up structure for maintaining a thread under a certain tension and at the same time taking up the slack comprising a plurality of pivotally mounted tension fingers having substantially hook-shaped ends, resilient means for moving said tension fingers in one direction, a pair of co-acting guiding fingers projecting substantially at right angles to the tension fingers and acting to guide the

thread to the take-up structure, means for guiding the thread to said tension fingers, 60 and means forming an eye for guiding the thread from said tension fingers.

2. In a take-up and guide for shuttles, a plurality of swinging arms having substantially hook-shaped upper ends, the openings 65 in the hooks facing downward, means acting as a spring for resiliently holding the arms in a given position, a plurality of fingers projecting between said arms at a point below the hooks, said fingers acting 70 to guide a thread to a point against the arms below the hooks, and means for guiding the thread as it is being moved to a threaded position so as to strike said fingers and move thereover to a point against the 75 take-up structure.

3. In a take-up and guide for shuttles, a take-up structure including a body having a top plate provided with a pair of depending guiding members at one end, means co-acting with said depending members for guiding a thread to a given point, a take-up structure for receiving the thread at 80 said given point, said body being also formed with an outlet eye provided with a 85 projection extending from near the entrance point of the eyelet toward said guiding members.

4. In a take-up and guide for shuttles, a guide structure including a body having a 90 top plate merging into a pair of spaced depending guiding fingers, a plurality of auxiliary guiding fingers extending substantially parallel to the top plate and co-acting with the first mentioned guiding fingers, 95 and means forming an outlet eye for the thread, said means including an extension extending into the eye for preventing accidental removal of the thread.

5. In a take-up and guide for shuttles, the 100 combination with a shuttle having a cut-out portion merging into a notch in one side of the shuttle, said notch having one curved edge, of a guide structure provided with a curved edge mating with the first mentioned 105 curved edge, said guiding structure being formed with an outlet eye having an entrance slot, one edge of the slot merging into the curved edge of the guide, a take-up structure arranged within said socket, and 110 means extending from the guide for guiding a thread during the threading action to a point engaging the take-up structure and to said eye.

JOHN RUSH.
